UNITED STATES PATENT OFFICE

ROBERT F. BRACKE, OF CHICAGO, ILLINOIS, ASSIGNOR TO CURTIS B. CAMP, TRUSTEE, OF
GLENCOE, ILLINOIS

VACUUM FEED CARBURETOR

Application filed December 18, 1926. Serial No. 155,598.

My invention relates to improvements in vacuum feed carburetors and more particularly that type of carburetor intended for direct connection with the main fuel supply tank of a motor vehicle disposed at or below the plane of the carburetor.

It is an object of my invention to provide a carburetor of this type in which the relative levels of the fuel supply tank and the carburetor will not affect the uniformity of the mixture. The mixture delivered by the carburetor will remain the same though the position of the fuel supply tank is varied as much as two feet above or two feet below the plane of the carburetor.

In the construction of this carburetor I have made use of the suction multiplying properties of the Venturi tube to offset the decrease in volumetric efficiency which would otherwise result from the maintenance at the carburetor of a sufficient suction for lifting fuel to a height of 30" from the low level source of supply.

Sufficient suction or reduction of pressure is maintained at all times and under all engine conditions for lifting fuel the required height without the sacrifice of power at wide open throttle. The venturi is so designed and employed in the carburetor that it produces the necessary fuel lifting suction when subjected to a comparatively low induction chamber or manifold vacuum. The Venturi tube is continually under the action of induction chamber depression and thereby insures the delivery of fuel for all operating requirements whether wide open throttle, partly open throttle or idling.

I have dispensed with the common form of float mechanism and employ instead an automatic fuel valve which by varying the size of the fuel passageway in accordance with various fuel supply levels, maintains proper volume of fuel delivered to the nozzle or venturi for every engine demand.

In the accompanying drawings:

Fig. 1 is a sectional view of an embodiment of my invention.

Fig. 2 is a top plan view of the carburetor illustrated in Fig. 1;

Fig. 3 is a sectional view along the line 3—3 of Fig. 2;

Fig. 4 is a side elevation of a portion of the carburetor showing the intake orifice of the Venturi tube and shutter plate, and

Fig. 5 is a view of a chassis showing the installation of my improved fuel feed carburetor.

Referring now to Fig. 1, I employ a body casing 1 having a primary air intake 2, an induction chamber 3 with a passage 4 therefor arranged for registration with the intake manifold of an internal combustion engine. A vertically moving air valve 5 is provided within the casing 1 and arranged to cooperate with the valve seat 6 for the purpose of restricting the flow of air into the induction chamber 3 from the primary air passage 2.

The lower end of the valve member 5 carries an air piston 7 which is disposed within an air dashpot 8 formed in the lower portion of the casing 1. A compression spring 9 is provided for normally maintaining the valve 5 upon its seat 6. Means for adjusting the tension of the valve 5 is provided in a counter-acting adjustable spring 10 which bears at its upper end upon the stem of the valve 5 at 11 and which has its lower end bearing upon a threaded adjustable thumb screw 12. Screw 12 is further provided with a resilient locking member 13 for preventing the unintentional rotation thereof.

Further means for adjusting the tension of the valve 5 such as might be required during the changes from season to season is supplied by an arm 14 which extends radially from the sleeve 15 in which the screw 12 is held. The sleeve 15 is constructed to slide vertically in the portion 16 of the lower wall of the casing 1. A compression spring 17 normally holds the sleeve 15 in an elevated position. The arm 14 rides at 18 upon an inclined surface 19 fastened in the lower wall of the casing so that oscillation of the arm 14 as by the movement of a control wire 20 (see Fig. 2) may vary the tension of the counter-acting spring 10.

Extending through a side wall of the casing 1 into the induction chamber 3 is a Ven-

turi tube 21 (see Fig. 3) which forms the only jet or nozzle in the carburetor.

Special attention is called to the fact that the Venturi tube, first, is disposed in a plane 5 transverse to that of the axis of the induction chamber or flow of air from the passage through the valve 5. This construction permits fuel to be introduced in a manner hereinafter described, with the least possible resistance, and unlike those types of carburetors in which a vertical nozzle for introducing a rich mixture of air and fuel is found. Second, the axis lies in a diametrical plane of the induction chamber. I have found by 10 exhaustive experiments that this position of the venturi provides for the most efficient operation thereof.

This Venturi tube is designed to produce a vacuum at its throat 22 which at low engine speeds exceeds the induction chamber 20 vacuum by three to one. In other words, at idle or low speed wide open throttle the induction chamber shows a pressure reduction of about 9" of gasoline, whereas the suction formed at the throat of the venturi reaches about 27" of gasoline. This differential or ratio decreases as the speed of the motor increases. At 2000 R. P. M. wide open throttle, for example, the induction 30 chamber vacuum reaches about 30" of gasoline and the Venturi throat slightly more than 38".

The throat 22 of the Venturi tube is provided with a plurality of fuel holes 23 which 35 are comparatively large, thereby eliminating the possibility of clogging. Provision of these large holes is made possible by the fact that they are not called upon to meter or restrict the flow of gasoline for proper 40 mixture proportioning. Metering of fuel is brought about by other means presently described.

The holes or ducts 23 communicate with an annular passage 24 which in turn is connected by means of a fuel passage 25 (see 45 dotted lines Fig. 2) with a fuel chamber 26.

The chamber 26 is provided with a fuel valve 27 for controlling passage of fuel therethrough. The valve 27 is normally held 50 against its seat 28 by means of a compression spring 29. A strainer plug 30 is disposed at the lower end of the fuel chamber for removing extraneous particles of matter from the fuel as it enters the chamber through 55 the feed passage 31.

Forming the top wall of the chamber 26 is a thin metallic diaphragm 32, the upper side of which is subjected to atmospheric pressure. When the pressure within the 60 chamber 26 is that of the atmosphere the valve 27 is closed and there is a very slight clearance between the valve and the diaphragm.

The diaphragm 32, fuel valve 27 and the 65 spring 29 so cooperate with the venturi to

provide a certain predetermined reduction of pressure within the chamber 26 when the carburetor is in operation. This pressure reduction may be varied by varying the tension of the spring 29.

A rigid metal cover 33 is provided over the diaphragm 32 and serves to bind the diaphragm in close engagement with the adjacent wall of the chamber 26 at its periphery, thus maintaining the diaphragm taut.

A cylinder 34 is formed in the upper wall of the cover 33 and a piston 35 is disposed within the cylinder. The cover 33 is further provided with a passage 36 therethrough connecting the cylinder with the chamber 26 above the diaphragm. A compression spring 37 tends to hold piston 35 in an elevated position.

The piston 35 forms with the cylinder 34 an accelerating means for causing momentarily a relatively rich mixture of fuel upon the sudden downward movement of the piston. Such momentary enriching of the fuel mixture is necessary whenever the throttle is quickly opened from idle position and to insure the automatic operation of the accelerator piston a bell crank 38 is mounted at 39 upon the casing 1 and has one end connected with the piston and its opposite end provided with a roller 41 which rides upon a cam 42 carried by the shaft 43 of the induction passage throttle valve 44. It will thus be seen that upon the opening of the throttle the depression of the piston will be caused and consequently a rise in pressure above the diaphragm results to move the valve 27 to a greater open position than existing at the time. Under normal running conditions the clearance between the piston 35 and the cylinder 34 permits atmospheric pressure above 90 the diaphragm.

Mounted upon the throttle shaft 43 and arranged to extend over the inlet orifice 45 of the Venturi tube 21 is a shutter plate or economizer 46. This shutter serves the function of restricting the flow of air through the venturi and thereby controlling the amount of suction produced at the throat thereof. In a venturi such as used on this carburetor the highest efficiency or in other words the highest throat vacuum is attained when there is present a free and unrestricted flow of air through the venturi. If this flow of air is restricted, the throat vacuum drops correspondingly until the point where throat vacuum equals that of induction chamber depression. Obviously when this happens there can be no fuel delivery.

The outermost edge of the shutter 46 is irregular in contour, having its outermost portion at 47 so formed as to lie in registration with the axis of the venturi when the throttle 44 is opened to that extent necessary to cause movement of the vehicle through speeds between ten and forty miles per hour on good 125 130

pavement and under favorable traction conditions. This is because it is desirable that these speeds run on as lean a mixture as is possible for good performance.

- 5 With reference to Fig. 3, it will be seen that the shutter plate 46 does not contact at any time with the adjacent face or end of the venturi 21 but is spaced at a slight distance therefrom. I have found that by so
 10 disposing the plate with respect to the venturi that the formation of eddies in the orifice of the venturi is less apt to occur than where the shutter is moved in contact with the end of the venturi to restrict the orifice 45.
 15 Means for maintaining the plate 46 in definite spaced relationship with the outer face or end of the venturi is provided in a spacer plate 48 which is fixed with respect to the plate 46 which contacts with the outer face
 20 or end of the venturi. A set screw 49 and arcuate slot 50 in the plate 46 serve to permit adjustments of the plate 46 with respect to the throttle shaft 43.

In explanation of the operation of this carburetor, let us assume the device is mounted for operation on an engine with the throttle 44 opened to a degree permitting the car speed of approximately 20 miles per hour. A suction or pressure reduction is created in
 25 the induction chamber 3. This suction is of course formed by the action of the air valve 5 and measures about 20" of gasoline by manometer test. The differential in pressure between atmosphere and induction chamber
 30 causes the air to flow through the Venturi tube 21, thereby producing a suction at its throat which is in excess of 30" of gasoline measured in a manometer tube. This increased suction is communicated directly to
 35 the under side of the diaphragm 32.

The diaphragm 32, fuel valve 27 and spring 29 are so adjusted that when a suction equivalent to 30" of gasoline is formed in the fuel chamber 26, the diaphragm is depressed by
 45 atmospheric pressure, thus opening the fuel valve against the tension of the spring 29. Fuel communication is thereby established between the Venturi tube and the main fuel supply tank 54 of the vehicle. The vent provided in the main fuel tank maintains the fuel therein under atmospheric pressure at all times.

It is apparent from the foregoing that fuel is delivered into the throat of the venturi
 55 where it is mixed with air flowing thereto. A second mixing takes place when the first rich mixture of fuel and air is delivered into the induction chamber. Here the primary mixture enters the stream of air flowing upwardly around the valve 5 and passes on through the manifold and into the various cylinders of the engine.

The quantity of fuel which is delivered into the induction chamber of the carburetor depends upon the differential or difference in

pressure which exists between the fuel valve 27 and the Venturi throat. If the suction is increased at the Venturi throat, leaving the restriction of the fuel valve 27 constant, there is an increase in the flow of fuel. Conversely, if the suction is decreased the mixture then becomes lean. If a less restriction is obtained at the fuel valve 27, leaving the venturi action constant, the mixture is enriched and the mixture is made lean by placing a greater restriction at the fuel valve 27.

It is therefore apparent that the amount of fuel delivered at the Venturi nozzle into the induction chamber is entirely dependent upon the differential existing between the nozzle and the fuel valve restriction. Let it be assumed now that the level of the fuel is raised to about that of the carburetor, assuming further that in the foregoing the level of fuel in the main supply tank was 20" below the carburetor. Without an automatic regulating means, the mixture delivered under these conditions would be exceedingly rich, but with the diaphragm mechanism which I employ, the mixture proportion remains fixed. With the main tank above the carburetor or at a level higher than that before mentioned, fuel flows into the fuel chamber with greater ease. A greater flow of fuel into the fuel chamber results in an increase of pressure in that chamber because the restriction at the nozzle prevents the withdrawal of fuel from the fuel chamber as rapidly as it has flowed thereto under these new conditions. As this pressure increases the diaphragm moves upwardly with the result that the fuel valve is moved toward its seat to form a greater restriction than before. Thus conditions immediately become stabilized and although the pressure in the fuel chamber will be slightly less than before, the difference will be so slight that it will have an unnoticeable effect upon the mixture proportions.

A substantially constant vacuum in the fuel chamber 26 is thereby automatically maintained by the varying opening of the fuel valve 27 as the fuel chamber vacuum is held substantially fixed regardless of fuel supply level. The differential existing between the fuel chamber 26 and the induction chamber 3 remains so nearly constant, a mixture of unvarying proportions is maintained.

As heretofore stated, under ordinary conditions it is desirable to have as lean a mixture as possible between speeds from ten to forty miles per hour upon good roads or pavement. When the throttle 44 is opened to maintain such speeds, the economizer shutter 46 is moved where it restricts the suction at the throat of the venturi, thereby causing less fuel to flow into the induction chamber. The irregularity in the outer edge of the plate 46 brings about the necessary

varying restriction of the venturi at varying throttle openings.

For a full wide open throttle the shutter is moved entirely out of registration with the venturi so that a full and unrestricted flow of air passes therethrough. This condition produces the highest suction at the throat of the venturi and thus enriches the mixture for full load maximum power. The correct mixture proportion for the different speeds at wide open throttle is secured by the proper induction chamber depression which is regulated by the air valve 5.

With the motor idling at the lowest possible speed, the air valve 5 is off its seat and admitting air into the induction chamber. This is made possible by the fact that the amount of air passing through the venturi is never sufficient for engine operation. At this speed and engine condition the economizer shutter 46 is entirely removed from registration with the venturi so that here as in wide open throttle position, the venturi nozzles may deliver that rich mixture which is necessary for best performance. The counteracting spring 10 provides the necessary adjustment for proper idling mixture and is regulated by turning the thumb screw 12.

Referring now to the accelerating means heretofore described, it will be noted that upon sudden opening of the throttle a pressure is applied to the upper side of the diaphragm 32 by the quick descent of the piston 35 in the cylinder 34. As a result of this increased pressure above the diaphragm, the fuel valve is opened to greater extent than for ordinary running and therefore richer mixture is delivered by the venturi or nozzle. This effect persists only for a few seconds, depending upon the clearance and rate at which the pressure is dissipated by leakage between the piston and cylinder walls.

With reference to Fig. 1, I have found that a rib 52 formed on the inner face of the cover 33 and concentric therewith eliminates the possibility of the buckling of the diaphragm 32 which might otherwise occur if by chance a diaphragm is employed which is not uniform in thickness throughout.

In Fig. 5 I have illustrated the relative positions of the carburetor and main supply tank 54 with respect to the motor 53a. 53 represents a chassis frame, and 55 the fuel feed line connecting the main supply tank 54 with the port 31 of the carburetor 1. It will be noted that in the present installation, the entire tank lies below the plane of the carburetor.

Having thus described my invention what I claim as new and desire to secure by Letters Patent of the United States is:

1. The combination in a carburetor of an induction chamber, a Venturi tube project-

ing into said chamber, a fuel passage communicating with the throat of the venturi for supplying fuel thereto, and a shutter plate disposed in registration with the air inlet orifice of the venturi parallel therewith and at a predetermined spaced distance therefrom for controlling the flow of air therefor.

2. The combination in a carburetor of an induction chamber, a Venturi tube projecting into said chamber, a fuel passage for conducting fuel to the throat of said venturi, and a plate disposed in a plane perpendicular to the axis of said venturi and at a predetermined spaced distance from the adjacent air inlet end of the venturi and arranged for movement in that plane, said plate being further provided with an irregular edge which overlies the orifice of the venturi upon movement of the plate to control the quantity of air admitted to the venturi.

3. The combination in a carburetor of an induction chamber, a throttle for said induction chamber, a Venturi tube projecting into said chamber, a fuel passage for conducting fuel to the throat of said venturi, and a plate disposed in a plane perpendicular to the axis of said venturi at a predetermined spaced distance from the adjacent air inlet end of the venturi and arranged for movement in that plane, said plate being further provided with an irregular edge which overlies the orifice of the venturi upon movement of the plate to control the quantity of air admitted to the venturi, said plate being connected with said throttle and actuated in its movement thereby.

4. The combination in a carburetor of an induction chamber, a throttle for said induction chamber, a Venturi tube projecting into said chamber, a fuel passage for conducting fuel to the throat of said venturi, a plate disposed in a plane perpendicular to the axis of said venturi and at a predetermined distance from the adjacent air inlet end of the venturi and arranged for movement in that plane, said plate being further provided with an irregular edge which overlies the orifice of the venturi upon movement of the plate to control the quantity of air admitted to the venturi, said plate being connected with said throttle and actuated in its movement thereby, and means for adjusting the plate with respect to its throttle connection.

5. The combination in a carburetor of an induction chamber, a Venturi tube projecting into said chamber, a fuel chamber, a fuel passage for admitting fuel to the throat of said venturi, suction operated means for controlling the passage of fuel to the fuel passage from said fuel chamber, and a plate disposed in a plane perpendicular to the axis of said venturi and at a predetermined distance from the adjacent air inlet end of the venturi and arranged for movement in that

plane, said plate being further provided with an irregular edge which overlies the orifice of the venturi upon movement of the plate to control the quantity of air admitted to the venturi.

6. The combination in a carburetor of an induction chamber, a throttle for said chamber, a Venturi tube projecting into said chamber, a fuel chamber, a fuel passage for admitting fuel to the throat of said venturi, suction operated means for controlling the passage of fuel from said fuel chamber to the fuel passage, and a plate disposed in a plane perpendicular to the axis of said venturi at a predetermined distance from the adjacent air inlet end of the venturi and arranged for movement in that plane, said plate being further provided with an irregular edge which may overlie the orifice of the venturi whereby movement of the plate will control the quantity of air admitted to the venturi, said plate being connected with said throttle and actuated in its movement thereby.

25 7. The combination in a carburetor of an induction chamber, a Venturi tube projecting into said chamber, a fuel chamber, a fuel passage for admitting fuel to the throat of said venturi, suction operated means for controlling the passage of fuel to the fuel passage from said chamber, a plate disposed in a plane perpendicular to the axis of said venturi and at a predetermined distance from the adjacent edge of the venturi and arranged for movement in that plane, said plate being further provided with an irregular edge which may overlie the orifice of the venturi whereby movement of the plate may control the quantity of air admitted to the venturi, 40 and acceleration means operable by said throttle for influencing said suction operated means when said throttle is quickly opened to cause an increased flow of fuel to the fuel passage.

45 8. The combination in a carburetor of an induction chamber, a Venturi tube projecting into said chamber, a fuel chamber, a fuel passage for admitting fuel to the throat of said venturi, suction operated means for controlling the passage of fuel to the fuel passage from said chamber, a plate disposed in a plane perpendicular to the axis of said venturi at a predetermined distance from the adjacent edge of the venturi and arranged for movement in that plane, said plate being further provided with an irregular edge which may overlie the orifice of the venturi whereby movement of the plate may control the quantity of air admitted to the venturi, 50 acceleration means operable by said throttle for influencing said suction operated means when said throttle is quickly opened to cause an increased flow of fuel to the fuel passage, and a spring actuated air valve for controlling the admission of air to said induction

chamber whereby the induction chamber depression may remain substantially constant.

9. The combination in a carburetor of an induction chamber, a Venturi tube projecting into said chamber, a fuel chamber, a fuel passage for admitting fuel to the throat of said venturi, suction operated means for controlling the passage of fuel to the fuel passage from said chamber, a plate disposed in a plane perpendicular to the axis of said venturi at a predetermined spaced distance from the adjacent edge of the venturi and arranged for movement in that plane, said plate being further provided with an edge formed to variably overlie the orifice of the venturi whereby movement of the plate may control the quantity of air admitted to the venturi, acceleration means operable by said throttle for influencing said suction operated means when said throttle is quickly opened to cause an increased flow of fuel to the fuel passage, a spring actuated air valve for controlling the admission of air to said induction chamber whereby the induction chamber depression may remain substantially constant, and means for adjusting the spring tension of said air valve to vary the induction chamber depression.

10. The combination in a carburetor of an induction chamber, means comprising a nozzle for admitting fuel to said induction chamber, suction operated means including a diaphragm for controlling the quantity of fuel admitted to said fuel feed means and other means associated with the suction operated means to affect said diaphragm for momentarily augmenting the flow of fuel through said nozzle.

11. In a carburetor of the character described, an induction chamber, a fuel feed means comprising a nozzle for admitting fuel to said induction chamber, a throttle for controlling the passage of fuel mixture through said induction chamber, suction operated means including a diaphragm for controlling the passage of fuel to said fuel feed means and other means operated by said throttle and associated with said suction means to affect said diaphragm for momentarily and uniformly augmenting the flow of fuel through said nozzle.

12. The combination in a carburetor of an induction chamber, fuel feed means for admitting fuel to said chamber, suction operated means including a diaphragm having one side at normally atmospheric pressure for controlling the passage of fuel to said fuel feed means, and means for momentarily increasing the pressure on the atmospheric side of said diaphragm to cause said suction operated means to admit momentarily a greater quantity of fuel therethrough.

13. The combination in a carburetor of an induction chamber fuel feed means for admitting fuel to the chamber, suction oper-

ated means including a diaphragm having one side subjected to atmospheric pressure for controlling the quantity of fuel admitted to the fuel feed means, a cylinder having a 5 passage communicating with the atmospheric side of said diaphragm, and a piston in said cylinder whereby said operation of the piston may increase the pressure on the atmospheric side of the diaphragm to cause 10 momentarily a greater flow of fuel to the fuel feed means.

14. The combination in a carburetor of an induction chamber, fuel feed means for admitting fuel to the chamber, a throttle for controlling the passage of fuel mixture through the chamber, suction operated means including a diaphragm having one side subjected to atmospheric pressure for controlling the passage of fuel to the fuel feed means, and other 15 means associated with the throttle and operated thereby for momentarily increasing the pressure on the atmospheric side of said diaphragm to cause a momentarily increased flow of fuel to the fuel means.

25 15. The combination in a carburetor of an induction fuel chamber, fuel feed means for admitting fuel to said chamber, a throttle for controlling the passage of fuel mixture therethrough, suction operated means including a diaphragm having one side subjected to atmospheric pressure for controlling the passage of fuel to said fuel feed means, a cylinder having a passage communicating with the atmospheric side of said 30 diaphragm, a piston in said cylinder, and means connecting the piston with said throttle whereby sudden opening of the throttle will cause light movement of the piston to momentarily increase the pressure on the atmospheric side of the diaphragm and increase the flow of fuel to the fuel feed means.

16. The combination in a carburetor of an induction chamber fuel feed means for admitting fuel to the chamber, suction operated means including a diaphragm having one side subjected to atmospheric pressure for controlling the quantity of fuel admitted to the fuel feed means, a cylinder having a passage communicating with the atmospheric 45 side of said diaphragm, and a piston loosely fitted in said cylinder whereby said operation of the piston may increase the pressure on the atmospheric side of the diaphragm to cause momentarily a greater flow of fuel to the fuel feed means.

50 17. The combination in a carburetor of an induction fuel chamber, fuel feed means for admitting fuel to said chamber, a throttle for controlling the passage of fuel mixture therethrough, suction operated means including a diaphragm having one side subjected to atmospheric pressure for controlling the passage of fuel to said fuel feed means, a cylinder having a passage communicating with the atmospheric side of said 55

diaphragm, a piston loosely fitted in said cylinder, and means connecting the piston with said throttle whereby sudden opening of the throttle will cause light movement of the piston to momentarily increase the pressure on the atmospheric side of the diaphragm and increase the flow of fuel to the fuel feed means.

In witness whereof, I hereunto subscribe my name this 19th day of October, 1926.

ROBERT F. BRACKE.
